UNITED STATES PATENT OFFICE

NEWTON M. DE ARMAN, OF VENTURA, CALIFORNIA

TANK FILLING APPARATUS

Application filed April 26, 1928. Serial No. 273,043.

This invention relates to tank filling apparatus and more particularly to apparatus for controlling the discharge of flow lines into a series of tanks.

An important object of the invention is to provide a construction such that a series of tanks may be connected to a single flow line and the flow line will successively discharge into these tanks and be disconnected from each tank when the fluid reaches a predetermined level in the tank.

A further object of the invention is the provision in apparatus of this character of a structure such that the flow line may be cut off from the tank with which it is in communication after a predetermined period of time without regard to the level of the fluid in the tank.

A still further object of the invention is to provide a construction such that the apparatus may be very easily prepared for successively filling the tanks.

A still further object of the invention is the provision of apparatus of this character which may be very cheaply constructed and readily applied to the tank, which will be durable and efficient in service and a general improvement in the art.

These and other objects I attain by the construction shown in the accompanying drawings, wherein for the purpose of illustration is shown a preferred embodiment of my invention and wherein:—

Figure 1 is a side elevation partially in section showing tank filling apparatus constructed in accordance with my invention applied to a series of tanks, two tanks of the series being illustrated;

Figure 2 is an enlarged side elevation partially in section of the control apparatus;

Figure 3 is a section on the line 3—3 of Figure 2;

Figure 4 is a sectional view through one of the guide pulleys of the control apparatus;

Figure 5 is a sectional view through the other of the guide pulleys;

Figure 6 is a fragmentary elevation showing the manner of connecting the brace and guide to the support;

Figure 7 is a fragmentary plan showing the time actuated operating drum;

Figure 8 is a sectional view illustrating a convenient means for locking the apparatus against unauthorized use.

Referring now more particularly to the drawings, the numerals 10 and 11 indicate successive tanks of a series in which there might be any number of tanks and 12 indicates a flow line for delivering fluid to said tanks. In accordance with my invention, I provide at each tank, with the exception of the last tank of the series, not illustrated, two valves 13 and 14, of which the valve 13 controls continued passage of fluid through the flow line to the succeeding tank of the series and the valve 14 controls communication between the flow line and the tank. In the present instance, these valves have been illustrated as seating in the same direction and as longitudinally spaced in the flow line.

Between the valves, I secure to the flow line a standard 15 at the upper end of which is pivoted a lever 16 having link connections 17 with the stems 18 of the valves 13 and 14. To the flow line, I secure, as indicated at 19, a standard 20 adjacent which one end of the lever 16 operates. This standard has a downwardly extending guide 21, which is spaced at its lower end from the standard to provide a guide slot 22 into which the end of the lever 16 may extend when the valve 13 is closed and the valve 14 is open. Pivoted to the standard, as at 23, is a latch 24, the upper end of which is provided with a shoulder 25 adapted to engage beneath the lever and hold it within the guide slot 22. The supports 19 likewise serve to mount one end of a bracket arm 26, the opposite end of which is connected with the upper end of the standard by a brace 27. This brace 27 is connected with the lever by a spring 28, which spring serves to maintain the latch 24 in its position beneath the lever 16.

Upon the flow line or some other suitable support, I mount a pair of pulleys 29 and 30. The pulley 29 guides a pair of flexible elements 31 and 32 which are connected to the lower end of the latch lever 24. The flexible

- element 31 is operatively connected to a float 33 arranged within the tank and is preferably guided to the bottom of the tank through a tube 34 or by some other suitable means.
- 5 The pulley 30 guides a flexible element 35 which is attached to the lever 16 at one end and at its opposite end is connected to one end of a spring 36, the opposite end of which is connected to the brace 27. The outer end of this lever is preferably provided with a counter-weight 37 to assist the spring 36 in its operation.

10 Mounted upon the bracket arm is a clock 38 having an alarm winding arbor 39 to which is secured a small drum 40 to which the opposite end of the flexible element 32 is secured in such manner that it is wound thereon when the alarm arbor rotates and thus serves to exercise a pull upon the latch lever, disengaging 15 the shoulder 25 thereof from the lever 16.

15 In the use of the device, where it is simply desired to successively fill the tanks of the series, the lever 16 of each tank of the series is forced upwardly until it is held by a latch 20 24. This places the valves 13 and 14 in such position that each tank is in communication with the flow line and the flow line is cut-off beyond the tank. As the float rises in the first tank, the flexible element 31 will exercise 25 a pull upon the latch 24, releasing the same and permitting the lever to shift under the influence of the spring 36 and counter-weight 37. The positions of the valves of this tank are thus reversed, communication

30 35 between the tank and the flow line being cut-off and the interruption of the flow line discontinued. The fluid will accordingly flow into the second tank of the series where the above operations will be continued. The last 40 tank of the series (not shown) will, of course, be provided with a plug closure for the flow line in lieu of the valve 13.

When a test is desired to determine the amount of liquid flowing through the line 12 45 at a given interval, the lever 16 of the tank or tanks where the test is to be made is placed in the position where the valve 13 is closed and the valve 14 open. The alarm mechanism of the clock 38 is then set to operate 50 at the desired interval and when this interval has passed, operation of the arbor will cause the flexible element 32 to be wound thereon, with the result that the latch 25 is withdrawn and the arm 16 shifted to its normal position by the weight 37 and spring 36.

If, for example, it is desired to determine the flow per hour for three hours, it is merely necessary to set the mechanism of the first three tanks of the series in the manner just described, the alarm mechanism of the first tank being set to operate at the end of one hour, that of the second tank at the end of two hours and that of the third tank at the end of three hours. By gauging the tanks at 60 65 the time of setting the apparatus and gaug-

ing them again at the expiration of the period, the delivery can be determined accurately.

Since the construction heretofore set forth is capable of a certain range of change 70 and modification without materially departing from the spirit of the invention, I do not limit myself to such specific structure except as hereinafter claimed.

I claim:

In combination, a filling line, a series of tanks connected thereto, a valve at each tank adapted to be closed to cut off the flow line from succeeding tanks of a series, a second valve at each tank and adapted to be opened 80 to permit delivery of fluid from the line to the tank, a lever pivoted between its ends and connected to the valves and adapted when raised to hold said first valve closed and said second valve opened, a bracket arm secured to the flow pipe, a standard secured to the bracket arm, a brace secured to the bracket arm and standard, a latch pivoted to the standard and engaging the lever whereby to hold the lever in upraised position, a spring connected to 85 the brace and lever for holding the latch into engagement with the lever, a float within the tank, and a flexible connection between the float and latch said float upon filling of the tank pulling said flexible connection for release of the latch from the lever against the tension of said spring.

In testimony whereof I hereunto affix my signature.

NEWTON M. DE ARMAN.
